ERNEST T. GILLIARD, OF HANOVER, PENNSYLVANIA.

VALVE-GEAR.

1,284,311.

Specification of Letters Patent. Patented Nov. 12, 1918.

Application filed January 6, 1917. Serial No. 140,994.

To all whom it may concern:

Be it known that I, ERNEST T. GILLIARD, a citizen of Switzerland, residing at Hanover, in the county of York and State of Pennsylvania, have invented certain new and useful Improvements in Valve-Gears; and I hereby declare that the following is a full, clear, and exact description thereof, reference being had to the accompanying 10 drawings, which form part of this specification.

This invention relates to engine valve gear, and particularly to valve operating devices of explosive engines.

15 This invention is especially designed for use with that type of engine employing twin valves, which are normally closed by springs and opened by suitable devices actuated from a cam; and the present invention resides in 20 novel means whereby both valves may be simultaneously operated from one push rod, and comprises peculiarly disposed and related co-acting levers whereby the valves may be unseated at the same time and to the 25 same extent.

30 I will explain the invention with reference to the accompanying drawing which illustrates a practical embodiment thereof, and will enable others to manufacture and 35 use the same, and the claims set forth in brief the essential features of the invention for which protection is desired.

In the embodiment of the invention herein shown the valves are closed by springs 40 and each is opened by the movement of a related pivoted lever, and one of such levers operates the other and is in turn itself operated by the push rod.

With this invention the two valves can be 45 simultaneously operated and each valve have the exact desired extent of movement.

Referring to the drawing, 1 designates 50 part of the cylinder of an engine, having a head 1^a provided with ports 1^b, 1^c adapted to be closed by similar valves 2^b, 2^c. The valve 2^b is normally closed by means of a spring 2^a interposed between a collar 2^o, on the stem 2 of said valve, and the head 1^a. Similarly valve 2^c is normally closed by 55 means of a spring 2^a interposed between a collar 2^o, on stem 2^a of said valve, and the head 1^a.

The valve 2^b is adapted to be unseated by 60 means of a rocking lever 3 pivoted at 3^b on a stud 1^m on head 1^a. One arm of lever 3 is provided with a bearing point 3^a which

engages the upper end of the stem 2. The other arm of lever 3 is provided with a bearing point which is adapted to be engaged by the upper end of a push rod 5, that may 60 be actuated by a cam, not shown, such as is usually employed on this type of engine, said push rod engaging lever 3 at the proper times and in such manner as to cause opening of the valve 2^b, or permit its closing. 65

A lever 4 is pivoted at 4^b on a stud 1ⁿ attached to head 1^a; and extends inwardly past stem 2^a of valve 2^c, and this lever 4 is provided with an intermediate bearing point 4^a which engages the upper end of the 70 stem 2^a.

The inner arm of lever 3 extends beyond the point 3^a and has a bearing point 3^c which is adapted to engage with an opposed bearing point 4^c on the inner end of lever 4; the 75 inner end of lever 3 overlapping the inner end of lever 4 as shown.

The bearing point 3^c is preferably formed by the rounded end of a bolt 3^e tapped through the lever 3, and which bolt can be 80 locked in adjusted position by means of a nut 3^d.

The bearing points 3^a, 4^a and 3^c, 4^c are so positioned relatively to the pivots 3^b, 4^b of the levers 3 and 4, that if the lever 3 be 85 rocked to open valve 2^b, valve 2^a will be also simultaneously opened. The extent of opening of the valves is determined by the extent of lifting movement of the rod 5. The extent of opening of the valves, in relation to the movement of the rod 5, being 90 proportionate to the distances of the bearing points 3^a, 4^a from the pivots 3^b, 4^b.

95 Preferably the bearing points 3^c, 4^c are so located that in the normal position the point of contact between 3^c and 4^c is exactly midway between the valve stems 2, 2^a; and when bearing point 3^c is depressed, by the oscillation of lever 3, the bearing point 4^a will be depressed to the same extent and 100 therefore the valves 2^b, 2^c will be opened to the same extent. The bearing point 3^c can be adjusted so that the two valves shall be operated simultaneously.

105 It will be seen that the valve mechanism illustrated will enable absolute similarity and synchronous operation of the two valves to be realized. The bearing points 3^c, 4^c being shown as located exactly midway between the centers 3^b, 4^b, and between the 110 stems 2, 2^a, it follows that the valves will be uniformly and synchronously operated.

2
What I claim is:

1. In valve mechanism, a pair of similarly opening valves each having a projecting stem, springs on the stems for moving the valves in one direction, an oscillating lever pivoted adjacent one of the stems and having an inner arm engaging said stem and extending past said stem toward the other stem, and an opposite arm extending outwardly beyond its pivot, a push rod engaging the outer arm of said lever to oscillate the same and move the valve against the spring; a second lever pivoted adjacent the other stem and extending past said stem and contacting therewith, the inner ends of said levers overlapping and contacting, substantially as described.
2. In valve mechanism, a pair of similarly opening valves each having a projecting stem, springs on the stems for moving the

valves in one direction, an oscillating lever pivoted adjacent one of the stems and having an inner arm engaging said stem and extending past said stem toward the other stem, and an opposite arm extending outwardly beyond its pivot, a push rod engaging the outer arm of said lever to oscillate the same and move the valve against the spring; a second lever pivoted adjacent the other stem and extending past said stem and contacting therewith; the inner ends of said levers overlapping and contacting and an adjustable screw tapped through the lapped end of one lever and engaging the lapped end of the other lever, substantially as described. 25 30 35

In testimony that I claim the foregoing as my own, I affix my signature.

ERNEST T. GILLIARD.
